J. G. JONES

SUCTION BOX FOR PAPER MAKING MACHINES

Filed Feb. 12, 1924

UNITED STATES PATENT OFFICE.

JOHN G. JONES, OF ROCHESTER, NEW YORK, ASSIGNOR TO EASTMAN KODAK COMPANY, OF ROCHESTER, NEW YORK, A CORPORATION OF NEW YORK.

SUCTION BOX FOR PAPER-MAKING MACHINES.

Application filed February 12, 1924. Serial No. 692,430.

To all whom it may concern:

Be it known that I, JOHN G. JONES, a citizen of the United States of America, residing at Rochester, in the county of Monroe 5 and State of New York, have invented certain new and useful Improvements in Suction Boxes for Paper-Making Machines, of which the following is a full, clear, and exact specification.

10 This invention relates to paper making machines and particularly to suction boxes over which the Fourdrinier wire with the paper stock is drawn for dehydration. One object is to provide a suction box which will 15 support the wire screen upon an anti-friction device throughout its entire area as it passes over the box, thus materially lengthening the life of the screen. Another object is to eliminate the usual scraping of the 20 screen upon the suction box, particularly at the points where it comes upon and leaves the suction box. Another object is to provide a uniform suction throughout the area of screen supported upon the rollers. An 25 other object is to support the roller bearings at intervals throughout their length. Another object is to reduce the friction upon the screen by supporting it upon the suction box on rollers which are driven at a 30 peripheral speed equal to the speed of the screen. Other objects will appear hereinafter from the specification, the novel features being pointed out in the claims at the end thereof.

35 Fig. 1 is a plan view of a suction box constructed in accordance with and illustrating one form of my device, the Fourdrinier screen being shown over a portion of the box;

40 Fig. 2 is an enlarged detail plan view of intermeshing rollers used in my device;

Fig. 3 is an enlarged fragmentary section showing the intermeshing rollers and roller supports;

45 Fig. 4 is a section taken through a portion of the suction box, showing another view of the rollers and roller supports, and

Fig. 5 is a section on line 5—5 of Fig. 1. In the present embodiment of my invention

50 tion there is a box 1 of rectangular shape having side and end walls 2 and 3, a bottom 4 and an open top 5 across the ends of which extend flanges 6, these flanges being connected by strips 7. The bottom 4 is perforated at intervals at 8 for the reception 55 of suction pipes 9, through which air and water are removed from the box.

Across the ends of the top of the box I provide rollers 10 which are mounted in grooves 41 cut in strips 7. These rollers 60 are carried by shafts 11 to which gears 12 are attached to be rotated through a power driven chain 13. Both rollers are, therefore, driven together at the same speed, which is that at which the Fourdrinier wire 65 screen 14 is moved.

Parallel to shafts 11 are a series of shafts 15 driven by sprockets 16 and 16' which are preferably alternately arranged with sprockets 16 on one side and 16' on the 70 other. This is done for the sake of proper clearance. On these shafts are mounted a series of rollers, preferably of two diameters alternately arranged, with the large rollers 75 17 spaced by the small rollers 18. These two rollers may be integral, as shown in Fig. 2 at A, although I prefer to make them separate, as shown at B in the same figure. The large rollers 17 are mounted to turn with shafts 15, as by attaching by pins 18'. 80

Since rollers 10 and 17 are all power driven at the speed with which the wire screen moves, friction between the screen and box is practically eliminated. The screen contacts with the box only along the flanges 85 6, and the movement of the screen to these flanges is caused by rollers 10 which raises the screen to the level of flanges 6 which, as shown in Fig. 5, are in a slightly higher plane than strips 7. The screen does not 90 touch strips 7 or the incline 9 connecting the strips and flanges.

Some paper webs are relatively wide and it is consequently preferable to support the rollers and shafts between the ends. For 95 this purpose I provide a support 20 having arms 21 extending upwardly therefrom, each arm having a curved seat 22 of such

a radius that it may engage and support a small roller 18. I find it convenient to stagger these arms, as indicated in Fig. 4, and the number of these supports is determined 5 by the width of the suction box.

As can be seen from Fig. 2, the rollers do not fit tightly together in their intermeshing engagement, but have openings or interstices 23 in between. This provides for 10 the suction which draws air and moisture through the screen, and by the even pattern formed by the rollers the suction is evenly distributed over the entire area. I find it advisable to vary the width of the 15 suction box according to the width of the paper web W formed between the decker straps D. With this system there is a water seal along flanges 6, and rollers 10, thus causing the moisture to be drawn evenly 20 from the entire suction area. The rollers 17 not only support the wire in a plane and provide an anti-friction bearing, but in addition tend to subdivide the suction area 25 into a plurality of small areas from which moisture can be evenly drawn.

Although I have shown a preferred embodiment of my invention in the drawing, obviously numerous changes may be made therefrom without departing from my invention. I desire to include as within the 30 scope of my invention all such changes as may come within the terms of the following claims.

Having thus described my invention, what 35 I claim as new and desire to secure by Letters Patent is:

1. In a paper making machine, the combination with a wire screen, of a suction box over which the screen may be drawn, 40 having a suction area including a plurality of overlapping rollers with interstices between the rollers, whereby the screen may be supported by the rollers as the suction acts through the interstices and screen to 45 draw moisture from a paper web being formed on the screen.

2. In a paper making machine, the combination with a wire screen, of a suction box over which the screen may be drawn, having 50 a suction area including a plurality of overlapping rollers with interstices between the rollers, and means to turn the rollers by power, whereby the screen will be supported by the rollers and will move freely there- 55 over as moisture is drawn from a paper web being formed on the screen through the screen and intersticed rollers.

3. In a paper making machine, the combination with a wire screen, of a suction box over which the screen may be drawn, having a suction area including a plurality of shafts, each shaft carrying a plurality of different sized rollers, the rollers on one shaft lying adjacent rollers on another shaft, 65 the different sized rollers lying in an over-

lapping relation one to another with interstices between the rollers, means for driving a shaft by power, connections between some of the rollers and the power driven shaft, whereby certain rollers are power driven to support with minimum friction a screen which may be drawn over the suction box.

4. In a paper making machine, the combination with a wire screen, of a suction 75 box over which the screen may be drawn, the suction box having a foraminous top suction area including a plurality of rows of shafts, large and small rollers mounted on the shafts, the rollers being arranged in 80 overlapping engagement with interstices in between, and supports between the ends of the shafts consisting of arms contacting with certain of the small rollers, whereby the shafts will be held substantially in the desired plane.

5. In a paper making machine, the combination with a suction box, of a foraminous top therefor over which a wire screen may be drawn, side flanges on the top, a roller spanning the ends of the side flanges for positioning the screen on the flanges, a plurality of different sized rollers mounted in overlapping relation with the screen carrying peripheries of the large rollers 90 in the same plane as the plane of the side flanges, whereby the entire screen will be carried by the rollers as it is drawn over the box with the exception of narrow edge 95 portions of the screen which may contact with the flanges.

6. In a paper making machine, the combination with a suction box, of a foraminous top therefor over which a wire screen may be drawn, side flanges on the top, a roller spanning the ends of the side flanges for positioning the screen on the flanges, and a plurality of rollers mounted with their screen carrying peripheries in the same plane as the plane of the side flanges, and a power 105 drive for the rollers adapted to move all the rollers with which the screen contacts at the same peripheral speed.

7. In a paper making machine, the combination with a suction box, of end walls for the suction box, rollers mounted in the end walls and projecting above the top of the end walls, side walls for the box having their top surfaces above the tops of the end walls, a plurality of intermeshing rollers 115 between the four walls, the tops of the rollers being substantially in the same plane as the tops of the side walls, whereby a screen being drawn across the suction box will be supported throughout the major portion of its area upon the rollers, and will contact with the box only across the side wall.

8. In a suction box for paper making machines, the combination with a suction box, 120

of end and side walls therefor, a plurality of different sized intermeshed rollers across the top of the box, the tops of the large rollers which may support a wire screen lying in a plane, the top of the side walls also lying in the same plane as the large roller tops, and the end walls lying beneath this plane, whereby a screen, supported by the rollers, will contact with the box along the side walls.

Signed at Rochester, New York this 4th day of Feb. 1924.

JOHN G. JONES.
